DESIGN FOR A NUTCRACKER

Isidore Davis, New York, N. Y.

Application May 16, 1946, Serial No. 129,736

Term of patent 7 years

(Cl. D44—1)

To all whom it may concern:

Be it known that I, Isidore Davis, a citizen of the United States of America and resident of the city of New York, county of Bronx, and State of New York, have invented a new, original, and ornamental Design for a Nutcracker, of which the following is a specification, reference being had to the accompanying drawing, forming a part thereof, in which the single view is a perspective of a nutcracker showing my new design.

I claim:

The ornamental design for a nutcracker, as shown.

ISIDORE DAVIS.
